ABSTRACT: A pump unit for use in a tank adapted to be filled with a hydraulic fluid to a predetermined fluid level is provided and members suspend the pump and motor assembly in the fluid tank normally below the fluid level. These suspending members are attached at spaced points to means carried by the walls of the tank and the attachment means include vibration dampening members. A valve unit is provided in the tank below a removable tank cover and above the predetermined fluid level for the tank.

PUMP UNIT

The present invention relates to a pump unit having a pump and associated motor immersed in liquid.

The use in hydraulic systems of pumps and motor units completely immersed in the oil tank of the system is becoming more and more usual. This procedure has been found to present significant advantages, particularly since the construction of both the pump and the motor can be simplified to a considerable extent.

One problem associated with this system is, however, one of mounting the unit in the oil tank so that vibrations from the unit are not transmitted to the surroundings to a disturbing extent. The unit is normally mounted to the bottom of the tank. This enables rubber vibration absorbers to be mounted between the unit and the tank bottom. The disadvantage with this solution, however, is that rubber is attacked by the majority of hydraulic oils, and hence the effective life time of the vibration absorbers is short. It is also possible to place the unit at the bottom of the tank without vibration absorbers therebetween, and to mount the vibration absorbers between the tank and the foundation. Vibration of the actual tank to a disturbing extent is prevented in this instance by using a relatively thick plate in the actual tank or parts thereof. This solution is not completely satisfactory either.

In addition, irrespective of the manner in which the vibrations are absorbed, the method of mounting the unit on the tank bottom used hitherto incur readily perceived difficulties when the unit must be dismantled for inspection, repair or maintenance.

The object of the present invention is to provide an arrangement whereby a pump unit can be mounted in an oil tank in such a manner that the aforementioned difficulties are circumvented. Damping of vibrations in accordance with the invention can be achieved in a very simple manner, and installation and dismantling of the unit is rendered much simpler.

In accordance with the present invention, the pump unit is suspended in the upper portion of the tank above the level of the liquid. The pump unit can thus be suspended from attachment points mounted to or fastened with the walls of the tank with the vibration damping means positioned between the attachments and the walls, so that the vibration dampers are situated above the level of the liquid and not subjected to attack therefrom. By securing the unit in this way it is relatively easy to remove from the tank.

Associated with the hydraulic system is a control valve to an inlet of which a line extends from the outlet of the pump passes. Furthermore, lines pass from other openings at the valve to the hydraulic operating devices in the system and a return line which opens into the tank for return of oil thereto. This valve can to advantage be placed on support means within the tank, suitably with a vibration damping means positioned therebetween. To prevent vibrations from being transmitted from the unit to the valve through the line, the line may consist wholly or partially of a hose. In a suitable embodiment, a substantially vertical hose is attached from the pump outlet to an elbow tube, from which an essentially horizontal hose

extends to the valve.

The invention will now be described with reference to the accompanying drawings, in which:

FIG. 1 shows an oil tank in longitudinal section provided with a unit mounted therein in accordance with the invention,

FIG. 2 shows a cross section of the tank.

In FIGS. 1 and 2 there is shown an oil tank 1, filled with oil during operation to a level which varies between levels *a* and *b*. The tank is provided with a cover plate 2 which can be fastened in a suitable manner to the upper surface of the tank. A unit consisting of a pump 4 and a motor 5 is arranged in the tank so that during operation at least the larger portion of the unit is immersed in the oil (below level *b*). The construction and design of the pump and motor are not within the purview of the present invention and will not be described in detail. The pump, for instance, may be an Imo-pump of well-known design and the motor a known type of electric motor, which are combined to form a unit.

In the embodiment of FIGS. 1 and 2, the unit 4, 5 is suspended by means of three steel wire ropes 6, 7, 8 which are attached to suitable attachment means on the unit and to beams 9, 10 in the tank by means of conical, cup-shaped vibration dampers 11, 12, 13 made of rubber.

The outlet of the pump 4 is shown at 20. Extending from the outlet is a pressure hose 21, extending up to a metal elbow pipe 23, from which a short hose 24 extends to an inlet at a control valve 25, from which lines depart to the hydraulic operating devices. The valve 25 is attached to the beam 10 and a beam 26, with an elastic pad member 27, 28 therebetween. A return line 29 passes from the valve to the oil tank.

The vibration damping means 11, 12, 13, which are attached so that they do not contact the oil, effectively dampen all transmission of vibrations from the unit to the tank. The hoses 21, 24 serve to prevent transmission of vibrations from the unit to the valve 25. If the resilient support pad 27, 28 alone is sufficient to dampen vibration, the hoses can be replaced with rigid conduit.

I claim:

1. A pump unit comprising a fluid tank adapted to be filled with hydraulic fluid to a predetermined fluid level, a detachable cover for said tank, suspending members attached at spaced points to attachment members carried by the walls of said tank below said cover and above said fluid level by means of vibration dampening members, a pump and motor assembly suspended in said fluid tank normally below said fluid level only by means of said suspending members, and a valve unit mounted in said tank below said cover and above said liquid level and having a fluid inlet operatively connected to a fluid outlet of the pump by means including a conduit.

2. A pump unit as in claim 1, where said conduit is flexible, and resilient means support said valve unit on a beam carried by the tank walls.

3. A pump unit as in claim 1, where said suspending members comprise wire ropes.

4. A pump unit as in claim 1, where a return line extends between said valve unit and the lower portion of said tank for return of fluid thereto.
